ANNEALING FURNACE

James C. Woodson, Cleveland, Ohio, assignor to
 Lee Wilson Sales Corporation, Cleveland, Ohio,
 a corporation of Ohio

Application October 5, 1940, Serial No. 359,888

4 Claims.

(Cl. 266—5)

This invention relates to a furnace and, in particular, to a furnace of the hood or cover type particularly adapted for the annealing of sheet metal, e. g., cold-rolled ferrous strip in coils.

Cover-type annealing furnaces have been used extensively and have exhibited satisfactory operating characteristics and a high efficiency. It is an object of this invention to improve generally on cover-type furnaces as known heretofore. As generally constructed, cover-type furnaces comprise a base or hearth and a cover proper, or hood, removably disposed thereon. The hood is provided interiorly with heat-exchange tubes whereby a charge of material on the base is brought up to the desired temperature. A metal protective cover is disposed over the charge before the heating cover is lowered on to the base.

I have invented a novel cover-type annealing furnace having numerous advantages over the conventional construction briefly described above. In a preferred embodiment, my furnace comprises a base having a charge support thereon, a refractory base ring removably disposable on the base and having a metal protective cover permanently united therewith. Heat-exchange tubes extend through the base ring and upwardly within the protective cover. A thermal insulating cover is removably disposable over the protective cover and is supported on the base ring. By this construction, the heat-exchange tubes are disposed close to the charge for direct radiation of heat thereto. This shortens the time which has been necessary heretofore to bring the charge up to the desired temperature.

Other novel features and advantages of my invention will be pointed out during the following detailed description of the preferred embodiment which is illustrated in the accompanying drawings. In the drawings,

Fig. 1 is a vertical, central section through a furnace according to the invention; and

Fig. 2 is a view partly in section and partly in plan taken along the plane of line II—II of Fig. 1.

Referring now in detail to the drawings, the base or hearth of the furnace is indicated generally at 10 and comprises a pier 11 of refractory brick laid up on a fabricated supporting frame 12 composed of welded plate. The frame 12 includes a peripheral sealing channel 13 and a central well 14.

A charge support 15 is disposed on the pier 11 and is provided with an annular base plate 16. The support 15 may conveniently be a casting and is provided with a central opening or eye 17 and radial passages 18. The base plate 16 is adapted to receive a charge of material to be annealed, e. g., a coil of strip 19.

A metallic protective cover 20 is fabricated of welded plate and comprises upper and lower por-

tions 21 and 22 of substantially cylindrical shape connected by a conical portion 23. The upper cylindrical portion 21 is provided with a top or roof 24. The lower cylindrical portion 22 is provided with an annular flange plate 25 which carries a refractory lining or base ring 26 extending therearound and upwardly therefrom beyond the joint between the portions 22 and 23. The portion 22 has a depending flange 27 adapted to enter the sealing channel 13 in the frame of the base or hearth 10. Eyes 28 extend outwardly from the lower portion 22 for cooperation with vertical guides 29 extending upwardly from the base 10.

Heat-exchange tubes 30 are spaced circumferentially around the interior of the cover 20. The tubes are generally of U-shape having spaced legs curving outwardly adjacent their lower ends as at 31 and 32. The upper ends of the tubes are suspended from the interior of the cover by links 33 cooperating with lugs attached to the tubes and the cover. The ends 31 of the tubes extend outwardly through openings in the base ring or lower portion of the protective cover 20 while the ends 32 penetrate the conical portion 23 of the cover.

Burner nozzles 34 are mounted in the lower ends 31 of the tubes 30. A fuel manifold 35 extends around the base ring, being supported on suitable brackets, and supplies fuel to the burner nozzles through suitable connections including individual control valves 36. An air duct 37 also extends around the base ring and connections 38 extend therefrom to the end 31 of each tube 30. Connections 39 and 40 extend from the manifold 35 and duct 37 to suitable sources of fuel and air, respectively. Above the air duct 37 is a cooling ring 37a through which water is circulated by suitable connections. The cooling ring prevents the heat to which the upper portion 21 and conical portion 23 of the cover 20 are subjected from flowing downwardly to the exposed sheathing enclosing the lower portion 22. A sealing channel 41 extends around the lower portion of the cover 20, being disposed adjacent the air duct 37 and supported on web plates 42 extending upwardly from the flange plate 25.

A thermal insulating cover 43 is adapted to be removably disposed on the cover 20 and comprises a refractory lining 44 assembled within an enclosure of welded sheathing plates 45. An annular flange plate 46 extends around the bottom of the cover 43. A depending flange 47 secured to the plate 46 has bearing pads 48 secured thereto adapted to rest on the bottom of the channel 41, thereby supporting the cover 43 on the cover 20. Eyes 49 extend outwardly from the plate 46 for cooperation with the guides 29.

Spark-gap igniters 50 extend through the wall of the cover 43 adjacent the ends 32 of the tubes

38 and are energized by transformers 51 carried on suitable mounting brackets 52. Sight openings 53 also extend through the wall of the cover 43. The top or roof of the cover 43 is provided with a central exhaust port 54 through which combustion gases are discharged to the atmosphere.

It is desirable to maintain a non-oxidizing atmosphere within the cover 28 throughout the annealing process. For this purpose, an inlet pipe 55 extends through the base 10 and is adapted to be connected to a source of non-oxidizing gas under suitable pressure. Outlet pipes 56 also extend through the base to permit an initial purging of the air trapped within the cover 28 and a continuous circulation of the non-oxidizing atmosphere, if desired. In order to permit the pressure of the atmosphere within the cover 28 to be observed, a tube 57 extends through the base and is connected to a suitable pressure-indicating device. Manometers 58 are mounted on the lower portion of the cover 28 and are connected to the fuel manifold 35 and air duct 37, respectively.

A motor 59 mounted in the well 14 of the base 10 has a shaft extending upwardly through a sleeve 60 penetrating the pier 11. A fan 61 is mounted on the shaft of the motor within the eye or central opening 17 of the casting 15. This fan, when driven, circulates the atmosphere within the cover 28 upwardly around the coil 19 and downwardly through the center thereof or vice versa.

In using the apparatus described above for the annealing of coils of strip, the covers 28 and 43 are lifted from the base 10 by a crane and a coil such as that shown at 19 is deposited on the base plate 16. The covers 28 and 43 are then lowered successively over the coil. After the air trapped within the cover 28 has been purged and the desired atmosphere established therein, fuel and air are admitted to the manifold 35 and the duct 37. The igniters 50 are then energized and ignite the combustible mixture issuing from the ends 32 of the tubes 30. After ignition, of course, combustion commences close to the ends of the nozzles 34 and continues throughout a substantial portion of the entire length of the tubes 30. These tubes thus become heated to radiant temperature and radiate heat directly to the coil 19. Absorption of heat by the coil is also facilitated by the circulation of the atmosphere within the cover 28 which is effected by the fan 61. Combustion gases issuing from the ends 32 of the tubes 30 flow upwardly past the upper portion 21 of the cover 28 and out through the exhaust port 54 in the cover 43.

When the coil 19 has been brought up to the proper temperature, the supply of fuel and air to the manifold 35 and duct 37, respectively, is discontinued and the cover 43 is lifted to permit atmospheric cooling of the coil 19. The cover 28 remains in position during the cooling stage. When the coil has been cooled to a temperature below that at which atmospheric oxidation proceeds rapidly, the cover 28 is raised, the coil 19 removed and replaced by another coil to be annealed, whereupon the cover 28 is again placed over the coil and the cover 43 lowered into position. It will be understood that a cover such as that indicated at 28 is provided for each base 10 in a multiple unit installation. A single cover such as that shown at 43 can be used successively in conjunction with different bases and heating covers.

It will be apparent from the foregoing description that the invention is characterized by numerous advantages over cover-type furnaces as heretofore constructed. In the first place, the location of the heat-exchange tubes within the protective cover greatly expedites the heating of the charge because the tubes are close to the charge and radiate directly thereto without any intermediate obstruction. Good thermal efficiency is obtained by reason of the long distance traveled by the combustion gases through both branches of the U-shaped heat-exchange tubes. Since the upper portion 21 of the protective cover 28 is permanently united with the lower portion 22 thereof, it is unnecessary to provide any seal for a joint within the cover 43. Since both the sealing channels 18 and 41 are on the exterior of the furnace, a liquid sealing medium may be employed. This provides better sealing than the sand seal which has been necessary heretofore inside the furnace cover.

Although I have illustrated and described but a preferred embodiment of the invention, it will be recognized that changes in the construction and arrangement of parts may be made without departing from the spirit of the invention or the scope of the appended claims. The base and covers, for example, could be made rectangular instead of circular, for the purpose of annealing sheets in stacks, instead of coiled strip.

I claim:

1. An annealing furnace comprising a refractory base and a refractory lined cover removably disposed thereon, said cover having a roof and side walls, said side walls being composed of separable upper and lower portions, a protective metal cover permanently united with said lower portion and extending inwardly of and upwardly within said upper portion, and heat-exchange tubes mounted inside said protective cover, one end of each tube penetrating the lower portion of said side walls, the other end of each tube penetrating the protective cover above the lower portion of said side walls.

2. In an annealing furnace, a base having a charge support thereon, a refractory wall removably disposed on said base, a protective metal cover including a top and side walls permanently united with said wall, heat-exchange tubes within said cover, one end of each tube penetrating the wall and the other end the side wall of the cover, an insulating cover removably disposable over said protective cover, and means on said wall for supporting said insulating cover.

3. An annealing furnace as defined by claim 2 characterized by the side walls of said protective cover including upper and lower substantially cylindrical portions connected by a frusto-conical, upwardly converging portion, said wall being laid in the lower cylindrical portion and of substantially the same diameter as said insulating cover.

4. In an annealing furnace, a base having a charge support thereon, a base ring of refractory material removably disposed on said base, a metal protective cover having a top and side walls permanently united to said ring, U-shaped heat-exchange tubes extending upwardly along the side walls of said cover, one branch of each tube penetrating said ring and the other the side wall of the cover, and an insulating cover removably disposed over said protective cover.

JAMES C. WOODSON.
